UNITED STATES PATENT OFFICE.

ROBERTE KLINGEL, OF HUNTINGTON, CONNECTICUT, ASSIGNOR TO MALTBY,
STEVENS & CURTIS COMPANY, OF SAME PLACE.

DESIGN FOR SPOON AND FORK HANDLE.

SPECIFICATION forming part of Design No. 12,234, dated April 26, 1881.

Application filed March 14, 1881. Term of patent 7 years.

To all whom it may concern:

Be it known that I, ROBERTE KLINGEL, of Huntington, in the county of Fairfield and State of Connecticut, have invented a new Design for Spoon and Fork Handles; and I do hereby declare the following, when taken in connection with the accompanying drawing, to be a full, clear, and exact description of the same, and which said drawing constitutes part 10 of this specification, and represents a face view.

This invention relates to a design for the ornamentation of the handle of forks, spoons, and like articles of table-service; and it consists in the ornamentation as shown in the accompanying illustration.

In outline the handle gradually expands from its narrower part toward the end, where it terminates in a semicircle. Diagonally across the

face of the handle, from the tip downward, is the representation of a floriated branch. From 20 the opposite side, and substantially diagonally across the face, is the representation of lace-work as hanging over the tip of the handle and in front of said branch, all as shown in the accompanying illustration.

I claim—

The design for the ornamentation of spoon and fork handles, consisting of the floriated branch running diagonally downward from the tip across the face, with the representation of 30 lace-work diagonally across from opposite sides, as shown in the accompanying illustration.

ROBERTE KLINGEL.
